ATTORNEYS.

UNITED STATES PATENT OFFICE.

GEORGE CLAPP, OF PHILADELPHIA, ASSIGNOR OF ONE-HALF TO THOMAS D. ABRAHAM, OF UPPER MERSON, PENNSYLVANIA.

GUN-WAD.

SPECIFICATION forming part of Letters Patent No. 396,986, dated January 29, 1889.

Application filed June 14, 1888. Serial No. 277,093. (No model.)

To all whom it may concern:

Be it known that I, GEORGE CLAPP, a citizen of the United States, residing in the city and county of Philadelphia, State of Pennsylvania, have invented a new and useful Improvement 5 in Gun-Wads, which improvement is fully set forth in the following specification and accompanying drawing.

My invention consists in forming a gun-wad of paper or other pulp and bristles, whereby the same is of superior nature and serves to scour the gun-barrel in its passage or exit through the same.

The figure represents a side elevation of a 15 gun-wad embodying my invention.

In carrying out my invention I combine paper or other pulp and bristles, and form a web or sheet of the same, from which web I punch out disks or pieces of the shape of gun-wads.

It will be seen that the wads may be quickly, 20 uniformly, and cheaply produced, and that they are comparatively solid or dense, so as to snugly fit the gun-barrel, and their peripheries present bent edges of hair or bristles, which serve to scour said barrel in their 25 exit, thus keeping the barrel in a cleanly condition.

Having thus described my invention, what I claim as new, and desire to secure by Letters Patent, is—

A gun-wad consisting of a composition of 30 paper-pulp and bristles, substantially as described.

GEORGE CLAPP.
